UNITED STATES PATENT OFFICE.

CHARLES J. SAGEBRECHT, OF TORONTO, ONTARIO, CANADA, ASSIGNOR TO INTERSTATE ELECTRIC NOVELTY COMPANY, OF NEW YORK, N. Y., A CORPORATION OF NEW YORK.

ELECTRIC POCKET FLASH-LIGHT.

1,187,105.

Specification of Letters Patent. Patented June 13, 1916.

Application filed January 31, 1916. Serial No. 75,290.

To all whom it may concern:

Be it known that I, CHARLES J. SAGEBRECHT, a citizen of the United States of America, residing at Toronto, Province of Ontario, Dominion of Canada, have invented certain new and useful Improvements in Electric Pocket Flash-Lights, of which the following is a full, clear, and exact description.

10 This invention relates to improvements in pocket flash-lights, but pertains more particularly to a special means to prevent a short circuit from being established between the circuit-closer on the casing, and 15 the lamp, through the reflector, the cap which retains the lens, and the sleeve which is engaged by the cap to hold the reflector and lamp in the casing.

I will now proceed to describe my invention in detail, the essential features of which 20 will be summarized in the appended claims, reference being had to the accompanying drawing, forming part hereof, wherein:

Figure 1 is a vertical sectional view of a 25 pocket flash-light embodying my improvement; Fig. 2 is a plan view of the flash-light, the reflector and lamp being removed; and Fig. 3 is a sectional view of the upper 30 portion of a pocket flash-light, the lens being removed, illustrating another embodiment of my invention.

In the accompanying drawing, the casing of a pocket flash-light is indicated by 1, and contains the ordinary battery 2. Each end 35 of the casing 1 is provided with the usual threaded sleeves 3 and 4 to receive caps 5 and 6 respectively. The cap 5 acts to hold the lens 7 and reflector 8 with its lamp 9 in position, the lamp contacting with the 40 carbon pole 10 of the battery 2. The cap 6 completes the circuit between the conductor 13 and battery 2 by means of the spring 11.

The circuit for the lamp 9 is completed 45 by means of the conductors 12 and 13 and circuit closer 14. The conductor 13 conveys the current to the circuit-closer 14, and the conductor 12 conveys the current to the lamp by aid of special means, to be described, when the circuit-closer 14 bridges the conductors 12 and 13.

The special means above referred to comprises an annular ring or bushing 15 (Fig. 1) located at the upper end of the bore of 50 the casing 1, said bushing being of conduct-

ing material and connected to the conducting strip 12. Current from the battery is conveyed to the lamp 9 by means of the strip 12, bushing 15 connected thereto, and reflector 8 which contacts with the upper 60 edge of said bushing. The reflector 8 is of course made of conducting material and is provided with a lamp-socket 16 to receive the lamp 9.

It is quite apparent that a circuit between 65 the circuit-closer 14 and cap 5 cannot be effected because the reflector, which is a part of the circuit, is out of contact with said cap, being kept out of contact therewith by the lens 7, which is of non-conducting material. Furthermore, the sleeve 3 is not connected to any current carrying part of the device and is separated from the bushing 15 by the casing 1. The cap 6 is the only externally positioned or exposed 70 current carrying element, excepting the circuit-closer 14, which is in circuit with said cap 6.

When the circuit-closer is at off position, it is impossible to complete the circuit for 80 the lamp through any other exposed elements of the device.

Fig. 3 illustrates another embodiment of my invention, which comprises a reflector 17 having a downwardly directed flange 18 85 which is connected to the conducting strip 12. In this latter form the reflector is not normally removable. In other respects the two devices are similar.

Having now described my invention, what 90 I claim and desire to secure by Letters Patent is:

1. In combination with the casing of a flashlight and the battery and lamp inclosed therein, a lens for said lamp, means for holding said lens in place, a conducting reflector in electrical connection with said lamp and held in place by said lens and said means, a conductor electrically connected to said reflector, a bushing fitting the interior 95 of the forward end of the casing and in contact with said reflector and conductor, but insulated from said lens holding means, a second conductor electrically connected to the pole of the battery remote from the lamp 100 and a circuit closing device movable at will into position to connect these conductors electrically together.

2. In combination with the insulating casing of a flash light and the battery and 110

lamp inclosed therein, a lens for said lamp, means for holding said lens in place, a conducting reflector in electrical connection with said lamp and held in place by said lens and said means, a conductor electrically connected to said reflector, a bushing fitting the interior of the forward end of the casing and in contact with said reflector and conductor, but insulated by said casing from said means, a second conductor electrically connected to the pole of the battery remote from the lamp, and a circuit closing device movable at will into position to connect these conductors electrically together.

3. In combination with the insulating casing of a flash-light and the battery and lamp inclosed therein, a lens for said lamp, means for holding said lens in place, a conducting reflector in electrical connection with said lamp, a pair of electrical conductors having

electrical connection respectively with said reflector and with the remoter pole of said battery, a circuit closing device arranged to connect the proximate ends of said conductors, and a bushing fitting the inner face of the upper end of the said casing and in contact with the reflector and the nearer one of said conductors, also positively insulated from the lens holding means at all points by said casing and assisting the lens and said means to hold securely in place the said reflector, a part of the latter being clamped between the lens and this conductive device as shown.

Signed at Toronto, Canada, this 26 day of January 1916.

CHARLES J. SAGEBRECHT.
